UNITED STATES PATENT OFFICE.

SYLVENUS WALKER, OF BOSTON, MASSACHUSETTS.

IMPROVEMENT IN INKSTANDS.

Specification forming part of Letters Patent No. 156,862, dated November 17, 1874; application filed June 17, 1874.

To all whom it may concern:

Be it known that I, SYLVENUS WALKER, of Boston, in the county of Suffolk and State of Massachusetts, have invented certain new and useful Improvements in Covers for Inkstands, of which the following is a specification:

The object of my invention is to provide a cover for fountain-inkstands which shall serve to assist in filling the same, and prevent the corrosion of the hinge-pin of the lid; and it consists of a metal collar, having at one side a circular curved shield, projecting upward from the inner portion or lid-seat of the collar, its upper portion being curved inwardly, so as to serve in filling the fountain when held in proper position, and, when in use upon such inkstand, shield the hinge-pin of the lid from corrosion by the evaporation of ink from the dipping-orifice, which is surrounded and covered by them. By this means the cover is confined to a small space upon the base of the inkstand, and, when the lid is thrown back or open, it rises but a short distance above the same, and consequently does not interfere with pen-holders placed upon a pen-rack attached to the base of such inkstands, or otherwise.

Figure 1 represents a vertical longitudinal section of the cover and fountain-inkstand combined. Fig. 2 is a top view of same with lid thrown back or open.

A represents the base of a fountain-inkstand, supporting a reservoir, B, upon the top of which is provided a pen-rack, C C C, all being constructed of one continuous piece of glass, (all of which is shown in my Patent No. 37,313, dated January 6, 1863,) and provided with a dipping-orifice, G, to which is shown attached a metal collar, H, provided with a curved vertical shield, K, to the outer or rear side of which is hinged the lid J, by the hinge-pin X passing through a portion of the lid and collar, in the usual manner.

My invention is more particularly designed for that class of inkstands in which the dipping-orifice is located at one side or in the base, the ink being held in an elevated fountain by atmospheric pressure being excluded therefrom, commonly known as fountain-inkstands, but is applicable to the general class of stands intended to have covers.

Having thus described my invention, what I claim is—

In covers for fountain or other inkstands, the collar H, provided with shield K, for the purpose specified, in combination with the hinged lid J, as set forth.

SYLVENUS WALKER.
